MARTIN J. KERMER
Jones' Bain
Hinkley 11/15

UNITED STATES PATENT OFFICE.

MARTIN J. KERMER, OF EVANSTON, ILLINOIS.

EVAPORATOR.

Application filed August 15, 1923. Serial No. 657,501.

To all whom it may concern:

Be it known that I, MARTIN J. KERMER, a citizen of the United States, residing at Evanston, in the county of Cook and State 5 of Illinois, have invented certain new and useful Improvements in Evaporators, of which the following is a specification.

The invention relates to evaporators.

One of the objects of the invention is to 10 increase the capacity efficiency of evaporators of the closed multi-effect type by providing an improved means for receiving its water of condensation and for the introduction of the water of condensation that comes 15 from another evaporator.

Another object is to provide means for 20 accelerating the circulation of the heated liquid material to more readily absorb heat from the heating agency by utilizing the differences in temperature in the path of circulation of the heated material.

Evaporators of the type referred to contain a chamber within which is located a bank or deck of tubes thru which the liquid 25 to be heated will pass. The space around the outside of the tubes is separated from the liquid within the chamber and steam is admitted into the outer space into contact with the exterior surfaces of the tubes to raise 30 the temperature of the liquid within the tubes and chamber.

It has heretofore been the custom to admit 35 water of condensation from another evaporator, of a series of effects, to the aforesaid steam space. When this water of condensation enters this steam space it comes in with such force and violence that it splashes up 40 on the outside surfaces of the tubes and covers large parts of their surfaces, thus preventing the contained steam from making contact therewith and, since the heated water does not give up its heat so readily as does the steam, even at a lower temperature, the available heating surfaces of the tubes is 45 thus diminished and the capacity efficiency decreased.

Another objection to admitting the water 50 of condensation into the space about the tubes is due to the fact that the staggered arrangement of the tubes causes them to interpose considerable resistance to the flow of the water, unnecessarily delaying its exit from the evaporator.

In carrying my invention into effect I 55 provide a special unobstructed annular path for the water of condensation from the pre-

vious evaporator, thru which this water may quickly pass to the exit and which path is located in a horizontal plane below the lower end of the tubes, thus preventing the water, or any part of it, from making contact with the outer surfaces of the tubes. Furthermore, I restrict the liquid down-take, within the evaporating chamber, near the lower end of this conduit, to accelerate the movement of the liquid, as it is about to enter the lower ends of the tubes, utilizing the velocity of the liquid in making more active circulation thru the tubes and causing greater absorption of heat.

Other objects, advantages and benefits will readily appear to persons skilled in the art, from a consideration of the following description when taken in conjunction with the drawing forming a part hereof, where- 75 in:

Fig. 1 is a section taken on line 1-1 of Fig. 2.

Fig. 2 is a part elevation and part section taken on a plane extending thru the longitudinal axis of the device.

In both views the same reference characters are employed to indicate similar parts.

The drawings are typical of evaporators 85 in general use with my improvements embodied therein, or composing a part thereof.

In the structure illustrated the outer casing 5 contains an evaporating chamber comprising an upper chamber 6, a lower chamber 7, and a connecting down-take 8, the latter extending thru the deck 9 containing the bank of tubes 10. The down-take tube is downwardly tapering, being considerably restricted at its lower end to accelerate the movement of liquid as it is about to enter the lower ends of the tubes 10, which are in the path of circulation. The tubes 10 of the bank also connect the chambers 6 and 7. The chamber or down-take 8 is surrounded by a relatively large tapered tube 11, which extends below the lower wall 12 of the deck 9. The deck 9 comprises the heating chamber bounded by the upper and lower crown plates 12, and the portion of the outside casing 5 and the tapered tube 11 connecting said crown plates 12. Between the tube 11 and the inner row of tubes 10 an annular space 13 extends. Below the space 13 is an annular trough 14 which constitutes a part 110 of my invention.

A pipe 15 passes thru the wall 16 of the

casing 5 into the trough 14 and on its upper end is secured a right angle elbow 17.

The heating water of condensation is introduced into the evaporator thru the pipe 15. The elbow 17 directs it into the circular path provided by the trough 14 in the direction shown by the arrows. Steam is immediately evolved from the heated water passing rapidly thru the trough and rises into the space within the deck, contacting all of the exterior surfaces of the tubes 10, and contributing to the heating effect of the steam already in this space. The water finds exit thru the pipe 18.

15 A partition 19 in the trough 14 prevents the water from continuing its movement thru the trough. The trough 14 also receives the water of condensation from the steam admitted through the steam pipe 22.

20 Air and some vapor is drawn from the interior of the deck thru the pipe 20 by the same means that exhausts the chambers 6, 7 and 8. A valve 21 controls the attenuation of the fluid or vapor content of the evaporating chamber.

After the hot water under pressure has made one circuit thru the annular trough 14, it will have given off all of the steam or vapor admissible, due to differences of pressure and, therefore, it may be quickly passed on to the evaporator of the next stage or effect.

The temperature of the liquid within the tubes 10 is higher than that in the sub-chambers 6, 7 and 8 and, therefore, the action of the water in the tubes is to rise into chamber 6, whereupon, as a result of displacement, water will flow into the lower end of the tubes to take the place of the hotter water that has flowed from their upper ends. The material contraction of the down-take tube 13 at its lower end will greatly accelerate the flow as it is about to enter the lower end of the tubes, thus by its momentum, making a more active circulation and rapid interchange of the liquid undergoing evaporation.

Having described my invention what I claim as new and desire to secure by Letters Patent, is:—

1. An evaporator comprising a casing

containing an evaporating chamber; a deck containing tubes connecting parts of the evaporating chamber separated by the deck; a steam chamber in the deck containing the 55 tubes and separated from the evaporating chamber; a trough in the steam chamber fully open to said steam chamber for conducting water through the steam chamber and located below the tubes and means for 60 forcibly projecting and directing the water thru the trough.

2. An evaporator comprising a casing containing an evaporating chamber; a deck containing tubes connecting parts of the 65 evaporating chamber separated by the deck; a steam chamber in the deck containing the tubes and separated from the evaporating chamber; an annular trough in the steam chamber 70 fully open to the steam chamber and located below the tubes, and a nozzle in the trough to project water thru the trough.

3. An evaporator comprising a casing containing an evaporating chamber, a deck 75 containing circulating tubes dividing the chamber into an upper and a lower sub-chamber; said sub-chambers connected by the tubes; a steam chamber in the deck containing the tubes; an annular trough fully 80 opening into steam chamber, located below the tubes and spanning the space therebetween; an inlet and an outlet pipe connected to the trough and a transversely extending partition in the trough between the pipes. 85

4. In an evaporator, an outer casing, a pair of spaced centrally apertured, upper and lower crown plates secured to said outer casing and a tapered tube joining the inner peripheries of said crown plates to enclose 90 a heating chamber, tubes passing through said heating chamber and secured in said crown plates, an annular trough in the bottom of said chamber, a nozzle horizontally arranged in said trough to inject condensed heating fluid from without into said chamber, an outlet in the bottom of said trough near said nozzle, and a partition between said outlet and nozzle.

In testimony whereof I hereunto subscribe my name.

MARTIN J. KERMER.
